UNITED STATES PATENT OFFICE.

KENT K. BRADDOCK, OF SAN FRANCISCO, CALIFORNIA.

DRAG-SCRAPER.

967,319.

Specification of Letters Patent. Patented Aug. 16, 1910.

Application filed February 21, 1910. Serial No. 544,976.

To all whom it may concern:

Be it known that I, KENT K. BRADDOCK, a citizen of the United States, residing in the city and county of San Francisco and 5 State of California, have invented new and useful Improvements in Drag-Scrapers, of which the following is a specification.

This invention relates to drag scrapers and particularly pertains to scrapers such 10 as are employed in moving and leveling earth in railroad construction and other excavating or dredging operations.

It is the object of this invention to provide a practical scraper having means by 15 which it may be loaded, moved, dumped, and handled automatically from a remote point, and which is substantial in construction and efficient in operation.

The invention consists of the parts and 20 the construction and combinations of parts as hereinafter more fully described and claimed, having reference to the accompanying drawings, in which—

Figure 1 is a side view of the invention in 25 a normal position. Fig. 2 is a plan view of the same with a portion broken away. Fig. 3 is a diagram illustrating the operation of the tripping device. Figs. 4, 5 and 30 6 are diagrams showing the invention in the various positions assumed in operation.

In the drawings A represents the body of the scraper which is constructed of suitable material, as sheet metal in box-like form, open on the top and on the front side. 35 The forward edge of the bottom of the scraper A is reinforced with a cutter plate B, which is beveled on its outer edge to form a blade C.

The plate B is inclined upwardly toward 40 its outer edge C and when rock-containing earth is to be handled it is provided with removable teeth D, which may be of any suitable number or design.

Mounted on the rear of the scraper body 45 A is a horizontally disposed shaft 2, which extends the width of the scraper A and may be either rigidly or revolubly secured thereto.

Revolubly suspended on each end of the 50 shaft 2 are sled-runners 3, a detail of which is shown in Fig. 3, and which are adapted to extend forward beneath the bottom of the scraper A, as shown in Fig. 1, thus supporting the latter above the surface of the 55 ground. These runners 3 may be constructed in any suitable manner, and are

preferably formed with a wide bearing surface, which is curved upward at the rear of the runner, as shown, and pivots on the fulcrum rod or shaft 2.

Pivoted at 4 on the inner side of each runner 3 at a point forward of and below the shaft 2 is a tongue or link 5, the outer ends of the tongues 5 being connected to a rod or yoke 6. A cable 7 has one end secured to the outer ends of the rod 6 through a crotch 8, as shown in Fig. 2, and passes around the respective outhaul and inhaul pulleys 9, 9', Fig. 1, and has its other end secured to the outer end of a crotched dumping lever or forked arm 10, which is pivotally mounted on the shaft 2.

An outhaul cable 11 attached to the pulley 9 extends in a direction rearward of the scraper A and passes around suitable direction pulleys 12 and leads to a winding drum 13, as shown in diagram in Figs. 4, 5, 6. From drum 13 leads back an inhaul cable 14 toward the forward end of the scraper A, and is connected with the pulley block 9'. 80 The inhaul cable 14 is also connected direct to the front of the scraper by a short section of cable 15 and the bail 16. These cables 11 and 14 are adapted to be wound upon the drum 13 from either direction, one paying 85 out as the other winds in. Drum 13 may be revolved by any suitable means and any desired type of winding drum, or series of drums, may be employed, as will be found expedient in the class of work the scraper is 90 to perform.

The operation of the invention is as follows: After dumping a load, to pull the scraper back to be put in position to scrape up a fresh load, the scraper is in the position shown in Figs. 1-6, with the scraper body A resting upon the sled-runners 3; the cable 11 being wound upon the drum 13 so as to exert a pull in the direction of the arrows in Fig. 6. As the cable 11 is wound 95 upon the drum 13, the inhaul cable 14 correspondingly unwinds. The scraper A is thus dragged to a position beyond the point from which it is desired to remove earth or other material, whereupon the drum 13 is reversed so as to pull upon the cable 14 in the direction indicated by the arrows in Fig. 4. This causes the block 9' to move forward so as to pull upon the cable 7, which pull causes the dumping arm 10 to move upward 100 and, by reason of a direct pull on the tongue 5, causes the forward ends of the runners

to move in a downward direction, thus raising the rear side of the scraper A into the position shown in Fig. 4. In this position the forward edge or blade C of the scraper 5 A is made to dig into the earth. Continued pull upon the cable 14 exerts a pull on the forward side of the scraper through the cable 15, drawing the scraper forward and scooping up a load of earth. The forward 10 movement of the scraper A and cable 14 causes the runners to upset, as shown in Fig. 5, and pulls the arm 10 into a vertical position and in contact with the back of the scraper A. In this position the forward pull 15 of the cable 14 is transmitted direct to the scraper body A, through the short cable 15 and the arm 10, so as to drag the scraper forward in horizontal position (Fig. 5) until the desired dumping point is reached.

20 When it is desired to dump the scraper A, the parts being in the position shown in Fig. 5, the drum 13 is reversed, bringing tension upon the outhaul cable 11 so as to retard the forward movement of the runners tempo- 25 rarily, and so pulling back upon the tongues 5, in opposition to the forward movement of the lever arm 10, and also drawing the block 9' against the lever 10 so as to slack the short cable 15. This action causes the for- 30 ward edge of the scraper to move downward while the rear portion is moved upward and forward, the shaft 2 acting as a pivotal point until the position shown in dotted lines in Fig. 5 is reached. In this 35 position the bottom of the scraper is more or less vertically disposed and causes the contents of the scraper to empty.

To restore the emptied scraper to the return unloaded position shown in Figs. 1 and 40 6, the cable 14 is slackened and cable 11 wound up, the runners first digging into the ground and then turning over into position, as shown in Fig. 6.

From the foregoing it will be seen that 45 this invention is particularly adapted to dredging inland ponds, lakes and like bodies of water, as the loading and dumping of the apparatus are controllable from the shore, thus enabling dredging operations to be carried 50 on at a distance, which is limited only by the stretch or span of the cable 11 and power of the motive engine. It will be manifest, however, that the invention is not limited to any particular use, but it can be 55 employed for excavating and grading purposes generally.

Having thus described my invention, what I claim and desire to secure by Letters-Pat- 50 ent, is:

1. The combination of a scraper, inhaul 60 and outhaul cables, and connections between the cables with means, whereby on the reversing of the direction of travel of said cables the bucket is tilted.

2. The combination with a scraper, of in- 65 haul and outhaul cables, flexible connections between the cables and also between the scraper and each of the cables, and means operative by said connections between the cables whereby on the reversal of the direction of travel of the scraper the latter is given an initial tilting movement.

3. The combination with a scraper, of run- 75 ners pivoted thereto, an outhaul cable connected to the runners, an inhaul cable connected to the scraper and also flexibly connected with the outhaul cable, and a dumping lever pivoted to the scraper and connected with said flexible connections between the cables.

4. The combination of a scraper, runners pivoted thereto, a dumping lever pivoted to the scraper adjacent to the pivot of the runners, flexible connections between the runners and said dumping lever, pulleys 85 through which said flexible connections run, an outhaul cable connected with one pulley, an inhaul pulley connected to the other pulley, and flexible connections between the in- haul cable and the front of the scraper. 90

5. The combination of a scraper open at the front end, a runner pivoted to the back of the scraper and extendible underneath and adapted to support the scraper, an in- haul cable connected with the front of the 95 scraper, and an outhaul cable connected with the runner.

6. The combination with a scraper open at the front, of a curved runner pivoted to the back of the scraper, and on which runner 100 the scraper is adapted to be supported and about which said scraper may also turn on a fulcrum, a dumping lever pivoted to the scraper adjacent to the pivot of the runner, a cable connected to the runner eccentric of 105 the pivot of the runner, inhaul and outhaul cables loosely connected with said flexible connections, and a flexible connection between the front of the scraper and the inhaul cable. 110

In testimony whereof I have hereunto set my hand in the presence of two subscribing witnesses.

KENT K. BRADDOCK.
